DESIGN FOR AN EMBROIDERED APPLIQUÉ

Herman Kaufman, New York, N. Y.

Application March 3, 1947, Serial No. 137,289

Term of patent 7 years

(Cl. D3—9)

To all whom it may concern:

Be it known that I, Herman Kaufman, a citizen of the United States of America, residing in New York city, county of New York, and State of New York, have invented a new, original, and ornamental Design for an Embroidered Appliqué, of which the following is a specification, reference being had to the accompanying drawing, forming part thereof, wherein the figure is a plan of an embroidered appliqué showing my new design on a dark background so as to bring out more clearly the details thereof.

I claim:

The ornamental design for an embroidered appliqué, substantially as shown and described.

HERMAN KAUFMAN.
